UNITED STATES PATENT OFFICE.

RICHARD RUEMELIN, OF ST. PAUL, MINNESOTA.

SAND-BLAST TUMBLER.

Application filed December 12, 1921. Serial No. 521,766.

This invention relates to improvements in tumbling barrels or tubs, as they are usually designated, and especially to devices wherein castings or other articles to be cleaned, or operated upon, are placed in a barrel or tub, which is rotated while the articles therein are acted upon by sand-blast jets. Devices of this kind are largely employed in the industries for removing dust, dirt, or scale from parts it is desired to clean, or upon which it is desired to expose a clean surface.

The principal object of this invention is to provide a tub or receptacle, rotatable on a fixed slope so as to cause the parts which are being cleaned to be agitated and rubbed against one another and against the inner surfaces of the receptacle, breakage of the parts being avoided by such rubbing action.

Other objects of the invention are to provide means for quickly discharging the parts from the tub or receptacle after they are cleaned; to provide for the oscillating of the sand-blast jets upon the parts to be cleaned, while such parts are being agitated in the revolving tub or receptacle, thereby rapidly and thoroughly cleaning all sides and surfaces of such parts; to provide means for enclosing the tub within a dust-tight ventilated casing thereby avoiding the objectionable escape of dust which would interfere with the gearing of the machine and cause annoyance to the operator; to provide the enclosing casing with electric lights for illuminating its interior; to provide a sight screen or window for observation of the parts while being cleaned; to provide a sand hopper inside of the casing for the collection of sand and dirt, with means for screening such sand, and for re-claiming and cleaning the sand that is capable of re-use, and to provide means whereby the oscillation of the sand-blast jets can be performed by mechanical power, or by hand power.

The invention consists generally in the constructions and combinations hereinafter described and particularly pointed out in the claims.

In the drawings:

Figure 1 is a plan section on line 1—1 of Figure 2, looking in the direction of the arrows;

Figure 2 is a front elevation and partial section, on line 2—2 of Figure 4;

Figure 3 is a side elevation showing the sand-blast jet oscillating mechanism; 55

Figure 4 is a sectional elevation on line 4—4 of Figure 1 looking in the direction of the arrows;

Figure 5 is a sectional elevation on line 5—5 of Figure 6, with the addition of the enclosing casing, which is also shown in section; 60

Figure 6 is a plan of the open tub or receptacle, looking in the direction of the arrows 6—6 of Figure 5; 65

Figure 7 is a sectional elevation on line 7—7 of Figure 8; with the addition of the enclosing casing which is also shown in section.

Figure 8 is a top view of the tub looking 70 in the direction of the arrows 8—8 of Figure 7;

Figure 9 is a vertical section showing a modified casing and oscillating mechanism.

In the drawings, 1 represents the cleaning receptacle which is preferably in the form of an open tub, the enclosing walls of which may be polygonal or cylindrical, and may be vertical, as shown in Figures 5, 7 and 9, or composed of flaring and vertical sections as shown in Figures 2 and 4, the latter construction producing a receptacle, the open top of which is smaller than the greatest diameter of the receptacle. The receptacle is preferably provided with a discharge door 2 secured in place by suitable hinges 4, and provided with a latch or lock 3. I may arrange in proximity to the low side of the tub, or receptacle, a suitable stationary chute or slide 5 (Figures 1 and 4). 90

The receptacle is also preferably provided with a bearing hub 6, preferably mounted upon a fixed shaft 7. This shaft is secured to a suitable pedestal, or stand 16, which is arranged to permit the shaft 7 to stand in an inclined position as shown in Figures 4, 5, 7, and 9. This pedestal may be braced by an inclined bar 18. The bearing hub 6 of the tub, or receptacle, is preferably provided with a beveled gear 8, suitably keyed or otherwise secured to said hub. 95

I also provide a driving or power shaft 9 mounted in suitable bearings 11 upon a stationary frame 17. The pedestal 16 and frame 17 are both preferably supported 100 upon a suitable base 19. The shaft 9 is pro-

vided with a beveled pinion 10 which engages the beveled gear 8 upon the hub 6. The shaft 9 is also preferably provided with suitable belt pulleys 12 and 12^a, the pulley 12^a being shown engaged by a driving belt 13. A friction clutch 14 is keyed or otherwise secured to the driving shaft 9 and a lever 15 is provided for engaging said clutch. The driving belt 13 may be applied either to the large pulley 12^a, or to the smaller pulley 12, and the tub or receptacle will be driven at a slow speed when the belt is in engagement with the large pulley 12^a, and at a higher speed when it is in engagement with 15 the smaller pulley 12.

The driving shaft 9 is preferably provided with a suitable cam 20 (Figure 3), and an oscillating lever 21, pivoted at 22 on a stud 64, arranged upon the machine casing, hereinafter described, is provided with a spring 23 which tends to hold the end of the lever 21 at all times in contact with the cam 20. A link 25 is pivotally connected by the pin 24 to the lever 21, and said link is provided with a recess or slot 26, adapted to engage a pin 27 on an arm 28. The arm 28 is secured upon one end of the shaft 29, mounted in supports upon the casing, hereinafter described. Two or more of the pins 27 may be provided on the arm 28.

A suitable sand blast nozzle 30 generally designated a gun, is supported upon the shaft 29, preferably by means of an adjustable clamp 34, and a hanger arm 32 to 35 which said clamp is connected, said hanger being pivotally supported by a suitable pin 33 upon a hub 31 that is secured to said shaft 29.

In Figure 9 oscillation of the blast nozzle is caused by the cam 20, and the sliding rod 68 operating against lever 28. Vertical adjustment of the blast nozzle is caused by the threaded portion 70 of hanger 32 and the lock nut 69.

In Figure 9 the door 41 is hinged at 42 on the rear side of the casing so that the door swings upward as shown by dotted lines.

The tub 1 may be discharged by an unlocking latch 59 and tilting the tub as shown in dotted lines, or the tub may be entirely removed from the casing 40 by the handles 60, and replaced by another loaded tub. The oscillating lever 28 Fig. 9 makes contact by pressure with the end of the sliding rod 68, so that by lowering the door 41 the oscillating lever is made to come in contact with the sliding rod.

The blast nozzle has connected to it a suitable hose 36 by means of which air under pressure for producing said sand blast may be introduced into the nozzle 30. A hose 35 is also connected to the sand blast nozzle 30, and this hose is provided at its lower end with a suitable sand sucker 37, prefer-

ably arranged in a box 38, adapted to hold clean sand, said box being preferably provided with a suitable sand sieve 39.

It will be understood that air under considerable pressure is supplied to the nozzle 30 through the pipe or connection 36, and that the suction created thereby lifts the sand from the sand box 38, bringing said sand into the air blast through said nozzle.

I make no claim in this application to the sand blast nozzle, or gun, that I use in this apparatus, although the blast nozzle or gun disclosed in my application for Letters Patent, Serial No. 474,791, filed June 3, 1921, I find to work very satisfactorily in connection with my present invention.

I prefer to arrange the tub or receptacle 1 in a suitable dust tight casing 40, the bottom of said casing 40^a forming, with the casing walls, a sand hopper for collecting the sand that passes out of the tub or receptacle into the casing. The casing 40 is preferably provided with a suitable door 41 having hinges 42 and a suitable latch 43.

I also prefer to provide the casing with a suitable observation window or screen 44 through which the operator may see the interior of the casing, and I find it desirable to provide within the casing an electric light 45 that brings the interior of the casing always under observation of a person looking through the window 44 into the interior of the casing, and, also owing to its inclined position, into the interior of the receptacle or tub.

I also prefer to provide the casing 40 with a ventilating pipe 46, which may connect with a suitable exhaust fan. When this tub 46 is employed I prefer to arrange a sand shield 47 within the casing to intercept any sand that might be drawn towards the said ventilating opening.

While the shaft 7 may be secured to the pedestal 6 by any suitable means I prefer to clamp this shaft in position by means of suitable U-bolts 48 that pass through openings in said pedestal, and are locked thereto by suitable clamping nuts.

I may also provide the shaft 7 with suitable ball bearings 49, to reduce the friction between the hub 6 and the shaft 7 (Figures 4 and 7).

I may also provide a suitable felt disc packing 50 to form a close joint where the hub 6 passes through the bottom 40^a of the casing 40.

For the purpose of permitting the sand that collects in the lower part of the casing 40 to escape therefrom, and pass through the screen 39 into the sand box 38, I preferably provide at the lowest part of the casing 40 a sand spout 51 having a suitable valve or damper 52 by which the passage of the sand from said screen 39 may be controlled.

- The casing 40 is supported in a stationary position preferably by any suitable supports. I have here indicated upright supports 53 connected to the base 19 and also to said casing. Said supports may be of any suitable form and construction that will hold said casing in a stationary position above said base, permitting the cleaning receptacle or tub to be rotated within said casing.
- 10 For holding the articles to be cleaned away from the floor and walls of the receptacle or tub I may provide suitable lugs 55 on the inner wall of the tub suitable lugs 56 on the bottom thereof.
- 15 In Figures 1 and 4 of the drawings I have shown the door 2 mounted upon vertical hinges 4 and arranged to discharge the articles from the tub or receptacle onto the plate or chute 5, from which they pass out 20 of the casing when the door 41 is open. In Figures 5 and 6 I have shown the door 2 hinged at the bottom, and capable of being turned down into the inclined position shown in dotted lines in Figure 5, where 25 the end of the door may rest upon a ledge 54 on the casing. In this construction the door itself forms a chute for the passage of the articles from the interior of the tub or receptacle to the outside of the casing.
- 30 In Figures 6, 7 and 9 I have shown the tub or receptacle 1 hinged at 58 to a projection 62 on the top of the hub 6, and held in position thereon by means of a latch 59, and a curved centering lug 61.
- 35 The bottom of the tub or receptacle is provided with suitable openings 66 through which the sand escapes into the bottom of the casing.
- I prefer to provide a suitable valve 63 40 for controlling the admission of air under pressure to the nozzle 30 for producing the sand blast.
- I have indicated by the curved line 65, 45 on Figure 4 of the drawings, the arc through which the sand spray oscillates while the machine is in use. This may, however, be lengthened or shortened by adjustment of the connection between the oscillating lever 21 and the arm 29 through the link 25 and 50 the pins 27.
- Operation.*
- In operating the device the articles to be cleaned are placed inside of the tub or receptacle 1 and the door 41 of the outer casing 55 is closed. The receptacle is caused to rotate by means of the beveled gear 8 and pinion 10, and one of the belt pulleys 12 or 12^a, power being applied through the friction 60 clutch 14 by means of the lever 15. If the belt is in engagement with the large pulley 12^a the receptacle is revolved at a slow speed, and at a higher speed if the belt is in engagement with the smaller pulley 12.
- 65 To start the sand blast jet air under pressure is admitted by means of the valve 63. Oscillation of the sand blast jet is caused by engaging the slot 26 of the link 21 with the pin 27, on the arm 28, the sand blast spray being thereby caused to sweep through an arc indicated at 65 in Figure 4. The position of this arc may be regulated by vertically adjusting the clamp 34 on the hanger 32 and horizontally by adjusting the hub 31 on the shaft 29. The throw or length of the arc 65 is regulated by connecting the link 25 with one or the other of the pins 27. For small charges of cleaning work the link 25 may be disconnected from the pin 27, permitting the sand jet to remain stationary while the tub is revolving, or permitting the sand blast jet to be oscillated by hand by means of the arm 28 and the shaft 29. The hanger 32 is preferably provided with a hinged joint 33 which permits the sand blast nozzle to swing parallel with the shaft 29, thereby avoiding damage to the nozzle or oscillating mechanism should the nozzle accidentally come in contact with the parts being cleaned in the revolving receptacle.
- The sand accumulating in the receptacle passes through the opening 66 and falling upon the inclined surface 40^a of the casing, accumulates in the bottom of the casing, and may be drawn out through the outlet spout 51, controlled by the discharge damper 52. The sand sieve 39 receives the sand from the spout 51 recleaning the good sand and depositing it in the sand box 39. The sand blast nozzle creates the sand blast jet and the vacuum that causes the sand to be elevated to the nozzle from the sand box 38 through the pipe 35 and the sand sucker 37. The dust generated during the cleaning operation is exhausted from the inside of the casing 40 through the exhaust pipe 46 which is connected with a suitable suction fan (not shown), while fresh air is admitted through the sight screen 44 and other openings. The articles being cleaned may be observed or inspected from the outside of the casing through the sight screen 44, the interior of the casing being illuminated by the electric light 45. After the parts are suitably cleaned the friction clutch may be disengaged causing the receptacle to come to a rest and the door 41 of the casing may then be opened giving access to the interior of the casing, and permitting the articles to be discharged therefrom.
- The details of the construction may be varied in many particulars without departing from my invention.
- I claim as my invention:
1. A closed housing, a hopper within the housing, gearing for rotating the hopper, including a drive-shaft, a rock-shaft traversing the housing above the hopper arranged transversely of the axis of rotation of the hopper and having a lever-arm outside

the housing, connections between lever and drive-shaft for oscillating the rock-shaft, a nozzle-carrier slidably adjustable upon the rock-shaft, and a nozzle vertically adjustable upon the carrier.

2. A closed housing, an axially inclined sleeve hub extending outwardly through and beneath the housing and rotatably supported, the upper portion of the housing

10 being mounted to swing upwardly, and a hopper hinged at the periphery of the hub so that when the hinging point is at its lowest level the hopper may rest on the lower portion of the housing, when swung 15 to discharge position, means for rotating the sleeve and means for circulating sand through the housing from above downwardly.

3. A closed axially inclined housing, an 20 axially inclined sleeve hub extending through and beneath the housing and rotatably supported, an upper portion of the housing being mounted to swing upwardly, and a hopper hinged at the periphery of the 25 hub so that when the hinging point is at its lowest level the hopper may rest on the lower portion of the housing, when swung to discharge position, means for rotating the sleeve hub, and means for circulating sand 30 through the housing from above downwardly.

4. A device of the class described comprising a casing having hinged together upper

and lower sections the parting line of said sections being diagonal, the upper section 35 adapted to swing upwardly, an inclined hub rotatable within the casing, an open top receptacle hinged at the periphery of the hub so that when the hinging point is at its lowest level, the receptacle may rest on the lower portion of the housing in a position to discharge its contents.

5. A device of the class described comprising an axially inclined casing, an axially inclined receptacle rotatable in the casing, 40 and open at the top, said casing having a discharge opening at the lowest portion of bottom, an air intake in its top portion, both on the same side, and an exhaust conduit 45 on the opposite side, the arrangement being 50 such that dust escaping from the top of the receptacle is prevented from reaching the lower discharge opening.

6. A closed housing, a hopper within the housing, gearing for rotating the hopper, including a drive shaft, a rock-shaft 55 above the hopper arranged transversely to the axis of rotation of the hopper, and having a lever outside the housing, connections between the lever and the drive shaft for oscillating the rock-shaft, and a nozzle carrier slidably adjustable lengthwise of the 60 rock-shaft.

In witness whereof, I have hereunto set my hand this 28th day of November, 1921.

RICHARD RUEMELIN.
